UNITED STATES PATENT OFFICE.

AUGUST JOSEPH KOWALSKY, OF RACINE COUNTY, WISCONSIN.

ASH PAN.

1,413,739.

Specification of Letters Patent. Patented Apr. 25, 1922.

Application filed June 7, 1921. Serial No. 475,684.

To all whom it may concern:

Be it known that I, AUGUST J. KOWALSKY, a citizen of the United States, residing in the county of Racine and State of Wisconsin, have invented certain new and useful Improvements in Ash Pans, of which the following is a specification.

This invention relates to ash receivers and the primary purpose thereof is to provide an improved form of ash receiver of the pan-type adapted for insertion in the ash pit of a furnace or the like to receive the ashes falling from the grate.

Another object of the invention resides in providing the receiver with side wings pivoted thereto and novel means for operating said wings.

A still further object of the invention is to construct the receiver almost exclusively of sheet metal to the end that the same may be readily and cheaply produced and consequently sold at a reasonable price.

In the drawings wherein I have illustrated a preferred embodiment of the invention Fig. 1 represents a top plan view of the receiver;

Fig. 2 is an end view thereof showing the side wings in open position;

Fig. 3 is a transverse sectional view through the receiver showing the side wings in open position and the operating means therefor in elevation;

Fig. 4 is an enlarged sectional view showing the manner of connecting the handle to the receiver and to the said side wings; and

Fig. 5, is a plan view of the blank from which the receiver body is constructed.

For the purpose of economy and to facilitate quantity production, it is my intention to construct the ash receiver of my invention as nearly entirely of sheet metal as is practical, and to this end the body of the receiver is preferably constructed from a sheet metal blank of the general shape shown in Fig. 5. In forming the said body the blank is first bent into box-like form to provide the bottom member 5, and the side and end members 6 and 7, respectively. The extreme ends of the side members 6 are somewhat reduced as is indicated at 8 and are bent inwardly at right angles to said sides so as to lie against the outer surfaces of the end members 7, as particularly shown in Fig. 2. A continuous reinforcing or binding wire 9 is preferably extended around the outer side of the members 6 and 7 adjacent the upper

edges of the latter, and is held in place by rolling backwardly thereover the said upper edges of the members as indicated at 10.

Sheet metal closures indicated at 11 are also provided and each closure has the ends thereof turned at right angle to provide the flanges 12. The outer edge of each closure is turned back upon itself as indicated at 13 to provide reinforcement at this point while the inner edge of each closure is rolled as indicated at 14 and is slotted in the rolled portion to accommodate the sheet metal hinge-straps 15 riveted to each side member 6. The said hinge straps 15 and the rolled edges of the closures 11 are connected by suitable hinge-pins or rods 16 passing therethrough.

To one flange 12 of each closure 11 there is pivoted an end of a link 17, the opposite end of said link being pivoted to a crank pin 18 carried by a disk 19. It will be understood of course, that there are two links 17 and two pins 18 arranged as shown in Fig. 3. The disk 19 is disposed adjacent the inner side of one of the end members 7, and is provided centrally with a trunnion 20 passing rotatably through the end member and squared adjacent its outer end for passage through a squared opening formed in a plate 21 disposed adjacent the outer side of end member. The extreme outer end of the trunnion is threaded to receive thereon a nut 22, which serves to hold the parts assembled.

To effect rotation of the plate 21 and consequently of the disk 19, I provide a handle in the form of a wire bail 23 having its ends suitably secured to the said plate 21 as indicated at 24.

In practice, the ash receiver is adapted to be placed in the ash pit of a furnace or the like with the closure members 11 open or disposed as in Fig. 3 to engage opposite sides of the ash pit. In such position the closure members 11 act as deflectors adapted to intercept and direct into the body of the receiver such ashes as fall from the grate at points beyond the sides of the receiver. When the receiver has been filled and it is desired to remove the same, the handle 23 is rotated to effect, through the medium of the disk 19, and link 17, closing movement of the members 11 thereby disposing the said members as shown in Fig. 1 in which position the said members serve to substantially close the upper part of the receiver body to confine the ashes therein.

The receiver may be conveniently lifted and transported by means of a large handle bail 25 pivoted to or carried by the side members.

Having thus fully described what I now consider to be the preferred embodiment of my invention I wish it to be particularly understood that I do not limit myself to the exact construction and arrangement of parts herein disclosed as the right is reserved to resort to such modifications and changes as may later be found desirable providing of course, that the latter do not depart from the spirit and scope of the invention as defined in the appended claims.

What I claim as my invention is:

1. An ash receiver open at the top, closure members pivoted thereto, a rotatable handle member carried by the receiver and links 20 extending between the handle and closure members adapted to effect opening and closing of said closure members.
2. An ash receiver open at the top, closure members pivoted thereto, a rotatable disk 25 carried by the receiver, links extending between said disk and closure members, adapted, upon rotation of said disk, to effect opening and closing movement of said closures and means for rotating said disk.
3. An ash receiver open at the top closure, members pivoted thereto, a rotatable disk 30

carried by said receiver, links extending between said disk and closure members and a handle member connected to said disk to provide for the rotation thereof.

35

4. An ash receiver open at the top, closure members pivoted thereto, a rotatable handle member carried by said receiver and disposed on the outer side of the latter, a disk connected to and rotatable with said handle member and disposed within the receiver and connections extending between said disk and closure members.

40

5. An ash receiver provided with movable closures, links connected to said closures and operable to shift the latter to open or closed position and a rotatable handle carried by the receiver having eccentric connection with the links to actuate the same.

45

6. An ash receiver open at the top, closures pivoted thereto, a disk positioned within the receiver and provided with a trunnion passing rotatably through a wall of the receiver, a plate fixed to a projecting portion of the trunnion, a handle bail carried by the plate to rotate the same and links connected between said disk and closure members.

50

In testimony whereof I hereunto affix my signature.

AUGUST JOSEPH KOWALSKY.
